UNITED STATES PATENT OFFICE

PETER PARLATO, OF NEW YORK, N. Y.

DESIGN FOR A LAMP TORCHIERE WITH LUMINOUS REFLECTOR

Application filed April 11, 1932. Serial No. 43,457. Term of patent 3½ years.

To all whom it may concern:

Be it known that I, PETER PARLATO, a citizen of the United States of America, and a resident of New York, county of New York, and State of New York, have invented a new, original, and ornamental Design for a Lamp Torchiere with Luminous Reflector, of which the following is a specification, reference being had to the accompanying drawing, forming a part hereof.

In the drawing:

Fig. 1 is a perspective view of the lamp torchiere with luminous reflector; and

Fig. 2 is a diagrammatic sectional view through the same to illustrate the spacing of the lower shade from the upper opaque reflector whereby light escapes to render the outer surface of the reflector self-luminous, the structural elements for supporting the parts in spaced relation being omitted.

I claim:

The ornamental design for a lamp torchiere with luminous reflector as shown and described.

PETER PARLATO.
